CLAIM

The ornamental design for a ceiling fan blade iron, as shown and described.

DESCRIPTION

FIG. 1 is a bottom perspective view of a ceiling fan blade iron in the environment of a ceiling fan, showing my new design;

FIG. 2 is an enlarged bottom perspective view of the ceiling fan blade iron of FIG. 1;

FIG. 3 is a bottom view of the ceiling fan blade iron in the environment of the ceiling fan;

FIG. 4 is an enlarged bottom view of the ceiling fan blade iron of FIG. 3;

FIG. 5 is a side view of the ceiling fan blade iron in the environment of the ceiling fan; and,

FIG. 6 is another side view thereof.

The ceiling fan shown in broken lines depicts environmental subject matter and forms no part of the claimed design.

1 Claim, 6 Drawing Sheets
